UNITED STATES PATENT OFFICE.

AUGUSTIN HENTSCHEL, OF BERLIN, GERMANY.

MACHINE FOR MELTING SNOW AND CLEANING STREETS.

SPECIFICATION forming part of Letters Patent No. 401,496, dated April 16, 1889.

Application filed November 26, 1887. Serial No. 256,272. (No model.)

To all whom it may concern:

Be it known that I, AUGUSTIN HENTSCHEL, fabricant, of Berlin, in the Kingdom of Prussia and German Empire, have invented a new and useful Machine for Melting Snow and Cleaning Streets, &c., of which the following is a specification, reference being had therein to the accompanying drawings, no patents being obtained by me anywhere for this invention.

My invention relates to a machine by means of which streets, court-yards, and the like may be cleared of dust or mud or of snow, water being employed in dealing with dust or mud, and heated water or a suitable chemical solution being used for melting snow, and the removal of the mud or slush from the path of the machine being effected by means of a helical scraper constructed as hereinafter set forth.

In the accompanying drawings, Figure 1 is a front elevation of the machine; Fig. 2, a side view; Fig. 3, an inverted plan showing the arrangement of the operating parts; Fig. 4, a cross-section of the helical scraper used for removing the mud; and Fig. 5, a longitudinal section through the cylinder *i*, which is used to water the roadway. Fig. 6 shows a plan of the machine, Fig. 1. Fig. 7 represents a central vertical section of the machine in the direction of the dotted center line, Fig. 3. Fig. 8 is a central vertical section of the machine, taken in right angle to Fig. 7.

The apparatus comprises a water tank or reservoir, *a*, inclosing a furnace, *b*, and mounted over the operating-gear upon a carrying wheel or roller, *c'*, in front and a rear wheel or roller, *c*, which latter by its rotation imparts movement to the operative parts of the machine. On the axle *d* of the roller *c* toothed wheels *e* are secured, and these, through intermediate gearing, *f*, drive the helical scraper *g*, and by means of the gearing *h* rotate the water-delivery roller *i* against the forward movement of the machine. The rollers *g* and *i*, as also the intermediate gear, are carried in frames *k* and are raised by means of connecting-rods *l l'* when the driver of the

machine mounts upon his seat *m*, Figs. 1, 2, and 7. The connecting-rod *l* is on its upper end 50 connected to the lever *l'*, centered at pivot *l''*. The other end, *l*', of the lever *l'* is hinged on the seat *m*, so that the end *l*' descends when the driver of the machine occupies his seat *m*. In this position the frames *k* are turned 55 upward on their center *d*, and the apparatus is out of action; and when it is to be put into operation the driver stands upon the step *n*, whereby the seat *m* is driven upward by springs *m'*, arranged underneath the seat *m*. 60

The scraper *g*, Figs. 2 and 4, is composed of a wooden roller having around its circumference webs or ribs *o*, of rubber or other elastic material, secured on edge in helical lines, these helically-disposed ribs being 65 designed to convey the mud and slush to one side of the machine on the rotation of the roller. To prevent the ribs *o* taking too hard a hold upon the roadway, the shaft carrying the roller *g* is fitted on both sides with roller-disks *p* of somewhat smaller diameter than the helical scraper. The water-delivery roller *i* is composed of a cast-iron perforated cylinder whose periphery is wrapped around with several layers of jute, manila, or other 70 textile material, *q*, through which the water percolates.

The wrapping of roller *i* with several layers of jute, manila, or other textile material, *q*, has for its object to distribute the water for 80 moistening the dust or melting the snow on a large surface. This roller serves a twofold purpose: In summer it serves to soften or moisten the dust or mud on the streets, while in winter it serves to melt the snow. The wa- 85 ter passes from the tank *a* to the roller *i* through a valve, *r*, controlled by the driver.

The valve *r* is operated by the driver of the machine in the following manner: On the back of the seat the connecting-rod *r'* is hinged, 90 which is fastened on its under end to the valve *r*, which regulates the outflow of the water out of the tank. When the driver of the machine has occupied his seat, the valve *r* is closed at the same time and the frames *k* are 95 elevated; but when the driver stands upon

the step n the springs m' drive up the seat m , and the valve r' opens, the outflow of the water entering the roller at both ends.

The machine may be drawn by animal draft or by mechanical means.

What I claim, and desire to secure by Letters Patent of the United States, is—

In a machine for melting snow and cleaning streets, the combination of tank a , furnace b , located therein, water-delivery roller i com-

posed of a perforated cylinder wrapped with jute, manila, or other textile material, q , connected with said tank, and helical scraper g , substantially as described.

In witness whereof I have hereunto set my hand in presence of two witnesses.

AUGUSTIN HENTSCHEL.
